UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

SWITCH-HEEL RAIL JOINT.

Application filed December 1, 1923. Serial No. 677,960.

To all whom it may concern:

Be it known that I, CLARKSON A. Disbrow, citizen of the United States, residing at New Rochelle, in the county of Westchester and State of New York, have invented certain new and useful Improvements in Switch-Heel Rail Joints, of which the following is a specification.

This invention relates to an improvement 10 in switch heel rail joints of the type wherein the switch rail is capable of being flexed about the rail joint as its fulcrum.

In practice, the joint at the heel of a switch connects a stationary rail with the 15 switch rail, and the point of the switch rail is movable laterally a maximum distance usually of approximately five inches. Prior to the use of heavy rail sections, which are now replacing very generally the 20 old lighter rail sections, there was no need to provide specially for any flexibility in the switch heel joint, as the switch rail itself had sufficient inherent flexibility to allow the point to be moved the required 25 distance. However, with the heavier rail sections now in use, and the correspondingly heavier joint bars, it is generally impossible properly and safely to throw the switch point without first loosening the 30 bolts in the joint at the end of the switch rail. As a matter of fact, it is quite common, in maintenance practice, to loosen sufficiently the bolts in the joint at the heel of the switch rail so as to permit freedom 35 for lateral movement whereby the switch point may be easily thrown from one position to the other. An objection to this practice, is that the loosened bolts allow for play, and this results in wear to the 40 parts.

This invention, therefore, primarily has in view the provision of a joint for use at the heel of a switch in which the bolts are kept tight at all times, yet permitting the 45 required lateral movement of the switch rail to be made without straining any part or parts of the structure.

With the above and other objects in view which will more readily appear as the nature of the invention is better understood, the same consists in the novel construction, combination and arrangement of parts hereinafter more fully described, illustrated and claimed.

Certain preferred and practical embodi-

ments of the invention are shown in the accompanying drawings, in which:—

Figure 1 is a top plan view showing the application of one form of my improved switch heel rail joint to a switch rail, and 60 contiguous fixed rail.

Figure 2 is a perspective view of the joint, the switch rail showing in section with its heel in the joint.

Figure 3 is a perspective view showing 65 another form of my invention as applied to a frog and switch joint, and

Figure 4 is a sectional view thereof.

Like reference numerals designate similar parts throughout the several figures of 70 the drawings.

In carrying the present invention into effect, it is proposed broadly to so construct the joint bars that each bar will have a greater flexibility at the switch rail end, 75 than at the other, thus permitting the switch point to be shifted laterally with ease, and without the necessity of loosening any of the bolts in the joint.

One application of the invention is illustrated in Figure 1 of the drawings, wherein the numeral 1 designates the main rail of a track, 2 the switch point rail and 3 the fixed rail of the switch, the rails 2 and 3 being disposed in alignment and connected by a joint 4. The joint 4 which is illustrated in Figure 2, is of the continuous-type, and includes joint bars 5—5, each bar comprising an upright fishing member 6 which fits the fishing spaces of the rails 2 and 3, a foot flange 7 which overlies the base flanges of said rails, and the base flange 8 which is integrally connected to the foot flange 7 and extends inwardly beneath said rails.

The joint bars 5 may be constructed in any suitable manner but usually and preferably by rolling mill and shearing operations, but regardless of the method of manufacture each joint bar of the joint shown 100 in Figure 2 of the drawings is made uniform in cross section throughout and one end thereof, that is, the end which engages the heel of the switch rail is altered or modified in such a way as to give it greater 105 flexibility than the other end. That may be accomplished in various ways, for instance, by cutting or forming a longitudinally extending tapering slot or kerf 9 in the foot flange 7 of the bar at the switch rail end 110

2

of the bar. The precise form and dimensions of this slot will, of course, be predetermined according to the weight and size of the switch rail and the "throw" thereof, but as shown the said slot or kerf has its outer wall 10 lying substantially parallel with the longitudinal axis of the rails, producing a form of slot or kerf giving considerable flexibility to that part of the joint 10 bar which fits in the fishing space of the switch rail. In this joint, the end portion of the fixed rail 3 has the support of the full section of the joint bars 5, and so has the extreme end of the switch rail 2 because said extreme end will have practically no lateral movement. The lateral movement of the switch rail will be progressively increased towards the switch end of the joint bars, and the slots 9 provide sufficient 20 space to permit the switch rail to be flexed laterally in either direction. Thus one end of the joint bar has one end of greater flexibility than the other. In order to increase the flexibility of the joint bars 5, I may 25 form the upright fishing member 6 of each bar with a longitudinal slot or kerf 11 which may extend inwardly from the switch end thereof. This slot 11 preferably, but not necessarily, communicates with the adjacent bolt opening 11' which is also formed in said fishing member. Thus, when the switch rail is shifted laterally the switch end portions of the joint bars 6 will be compressed by reason of their upper and lower 35 edges contacting with the fishing surfaces of the rail. The compression of this end of either joint bar gives to the switch rail an increased freedom in its lateral movement.

In Figures 3 and 4 of the drawings, the invention is shown applied to a frog and switch joint. This joint includes in its organization the switch rail 2, and the fixed rail 3 which are connected by the joint bars 12 and 13. In this form of construction 40 one of the joint bars, that is, the joint bar 12, is of the continuous-type which is provided with a base supporting flange 14 extending entirely across the undersides of the meeting ends of the rails, and also including the upright fishing member 15 and the foot flange 16. In this form of construction the foot flange 16 of the continuous-type bar is shown provided with a longitudinally disposed slot or kerf 17 extending 45 inwardly from one end of the bar and corresponding in location and function to the slot or kerf 9 shown in Figure 2 of the drawings. The opposite joint bar 13 in this frog and switch joint is of the angle bar type having the usual upright fishing member and the foot flange 16', said foot flange 16' being sheared or cut away at one end of the bar as at 17' to provide a flexible end portion of the bar to fit the 50 fishing space of the switch rail. Further-

more, this flexible end portion of each joint bar may be provided in the head thereof with a clearance recess 18 which reduces the area of contact between the heads of the bars and the undersides of the heads of the rails so as to contribute somewhat to the freedom of the heel of the switch rail within the joint. 70

From the foregoing, it will be seen that I have provided a switch heel rail joint 75 in which the joint bars are firmly clamped to the meeting end portions of the switch rail section and the fixed rail section and the joint bars are so constructed as to provide the switch ends thereof with greater 80 flexibility than the other ends, thus permitting the switch rail section to be shifted laterally in either direction with ease.

Without further description it is thought 85 that the features and advantages of the invention will be readily apparent to those skilled in the art, and it will, of course, be understood that changes in the form, proportion and minor details of construction 90 may be resorted to, without departing from the spirit of the invention and scope of the appended claims. 95

I claim:

1. A switch heel rail joint including a joint bar having one end of greater flexibility than the other. 95
2. A switch heel rail joint including a joint bar having the switch end of greater flexibility than the other. 100
3. A switch heel rail joint including a joint bar having at one end thereof a portion of the metal removed to provide greater flexibility at said end than at the other. 105
4. A switch heel rail joint including a joint bar having at one end thereof a longitudinally extending recess to provide greater flexibility at said end than at the other. 110
5. A switch heel rail joint including a joint bar having a foot flange, said foot flange having at one end thereof a portion of metal removed to provide greater flexibility at said end than at the other. 115
6. A switch heel rail joint including a joint bar having a foot flange, said foot flange having at one end thereof a longitudinally extending recess to provide greater flexibility at said end than at the other. 120
7. A switch heel rail joint including a joint bar having a foot flange, said foot flange having at one end thereof a longitudinally extending slot to provide greater flexibility at said end than at the other. 125
8. A switch heel rail joint including a joint bar having a foot flange, said foot flange having at one end thereof a longitudinally extending slot to provide greater flexibility at said end than at the other, the walls of the slot converging from the outer end of said slot. 130
9. A switch heel rail joint including a

joint bar having an upright fishing member, said fishing member having at one end thereof a portion of metal removed to effect a greater flexibility at said end than at the other.

10. A switch heel rail joint including a joint bar having an upright fishing member, said fishing member having at one end a longitudinally extending slot to effect a greater flexibility at said end than at the other.

11. A switch heel rail joint including a joint bar having an upright fishing member, said fishing member having a bolt opening formed therein adjacent one end thereof and having a longitudinal slot extending from said end and communicating with said opening to effect a greater flexibility at said end than at the other.

12. A switch heel rail joint including a joint bar comprising an upright fishing

member and a foot flange, said fishing member and flange being respectively formed with longitudinal slots at one end of the bar to effect a greater flexibility at said end than at the other.

13. A continuous switch heel rail joint comprising its fixed and switch rails, and joint bars connecting said rails and respectively having one end of greater flexibility than the other.

14. A switch heel rail joint including the fixed rail and the switch rail, of joint bars having slotted end portions engaging the heel of the switch rail.

In testimony whereof I hereunto affix my signature in the presence of two witnesses.

CLARKSON A. DISBROW.
